Matthew Matthews of the County of Wayne, Ohio

Letters Patent

The scheme referred to in these letters Patent and making part of the same, containing a description of the mode of construction, & the manner & method of his improvement in the boot-toe, —

To all those whom these presents shall come,

Be it known that I, Matthew Matthews of the County of Wayne and State of Ohio have invented a new and useful improvement in the boot-toe and the following is a full and exact description of the construction and operation of the boot-toe as improved by me, 1st The toe is made to consist of eight-ply, viz. A. 1. & an iron shank tapering from the widest place on the side to an edge, the shank is half an inch A. 2. even with the surface passing through A. 3. and from and nearly through A. 5. leaving a shoulder. The shank is seven inches long, two inches in width on the side, and half inch, in thickness and after passing this ball one inch, in thickness with a groove two inches in length, one-fifth of an inch in depth to receive the point of a suspender, and so to even, denominated the skin shoe for the purpose of raising the boot on the instep A. 3. The foot is divided into A. 3. by an upright stalk or the upper side of A. 2. as a plate of brass or copper made to fit a similar piece in A. 3. A. 2. the skin is a piece of wood made in the form of a big nail from the top to the middle of the skin on each side. A. 3. is attached to piece of brass to cover the cavity, made by the hinge A. 2. in as long division into A. 3. and so passing through without any notch of the foot at the top part of A. 3. so as to let water through the toe, which may be put to receive

46

a screw at 1:5, the back piece or collar a piece of wood made
 in the form of a half circle, as far as the middle of the collar con-
 taining a groove to receive a screw and wedge the groove is one
 and one $\frac{1}{16}$ th inch in depth, three $\frac{1}{16}$ th of an inch in width
 varying from the surface at the lower end, at the upper end of
 A: 6 is a mortise one and one half inch in length, one and
 one $\frac{1}{16}$ th inch in width the same in depth at the lower end
 of A: 5 is a mortise one half an inch in depth and one
 inch in width to receive the end of A: 1, A: 6. The
 perpendicular screw passing through A: 3 and A: 2,
 its point operating in the groove of A: 1, after the end on
 the bottom of A: 2, is a loop or iron nut, one and one half
 inch in length and of sufficient thickness to receive a screw
 one half an inch in diameter passing through the said nut
 acting on A: 1, to raise the collar A: 5, the height
 being three eighths of an inch in diameter passing through
 A: 3 and through a loop or iron nut inserted in
 A: 3, and through one or more rays, a point or extremity
 acting on a wedge part which is attached to A: 8 for the
 purpose of measuring the size of the boot at the top A: 8
 is a perpendicular screw eleven inches in length five eighths
 of an inch in thickness containing a groove nut, which nut is
 one and one half in length the same and one fourth inch in
 width and one and one fifth inch in depth to receive A: 7.
 These are attached to the collar A: 5 by a first pointed
 nail, the nail inserted in any one slot pointed with steel
 with a slate invisible collar to prevent the screw from
 separating from the nail, and all the screws being so arranged
 constituting a circular joint. The wedge is one and
 three $\frac{1}{16}$ th inches in length and one eighth of an inch in
 width and three fourths of an inch in thickness from the
 center bearing to a point downward, projecting from the
 center the wedge is made of copper and the top of this

47.

bar to which it is riveted by the point, the bar is one and three fourths inches in length, the extreme end of the bar, is a semicircle, with a tongue made to fit the apparatus of the wedge operation. The respective ends of the boat-tack are inserted in the boat, the facility by which the fasten is gained by the turning of N. 6 as appurtenant by those only who have tested its utility. 4:8. the screw and wedge increase the boat in size at the lower end 4:9. increasing the size of the boat at the tip. thus the necessity of hampering or defacing the boat, is dispensed with in a manner satisfactory to those who have witnessed the operation. Invention claimed I claim as my invention the peculiar form and construction of the boat hook, as above described 1st the perpendicular screw, 2nd the horizontal screw 3rd the screw and wedge 4th the plate of brass 5th the iron shank and dovetail groove all the above discoveries or improvements are dependent upon together with the privilege of carrying the proposition of maritime as may best suit my fancy so that I depart not from the principle therein set forth etc.
